Inventor
Emery Parker

United States Patent Office.

EMERY PARKER, OF NEW BRITAIN, CONNECTICUT, ASSIGNOR TO RUSSELL AND ERWIN
MANUFACTURING COMPANY, OF SAME PLACE.

Design No. 3,338, dated January 12, 1869.

DESIGN FOR THE FACE-PLATE OF A SASH-PULLEY.

The Schedule referred to in these Letters Patent and making part of the same.

To all whom it may concern:

Be it known that I, EMERY PARKER, of New Britain, in the county of Hartford, and State of Connecticut, have originated and designed a new Design for the Face-Plate of a Sash-Pulley; and I do hereby declare that the following specification, taken in connection with the drawings, making a part of the same, is a full, clear, and exact description thereof.

In the drawings—

A represents the face-plate of a sash-pulley;

B, the wheel; and

C, the wheel-mortise.

In order to give an ornamental effect to the plate, which, when attached to a window-frame, becomes a fixture, which is exposed to view, I surround the edge

of the plate and also the edge of the wheel-mortise with a raised moulding, *a*, whereby the effect of a sunken panel is obtained, and a novel and distinctive appearance given to the plate.

What I claim as my invention, and desire to secure by Letters Patent, is—

The design for the face-plate of a sash-pulley, which consists in surrounding the edge of the plate, or its edge and that of the wheel-mortise, with a moulding, as herein set forth and shown in the drawings.

EMERY PARKER.
